Attorney

UNITED STATES PATENT OFFICE.

GEORGE E. BUTLER, OF VALLEY FALLS, RHODE ISLAND, ASSIGNOR TO BROWN & SHARPE MFG. COMPANY, OF PROVIDENCE, RHODE ISLAND.

HAIR CLIPPERS AND THE LIKE.

Application filed September 25, 1925. Serial No. 58,583.

This invention relates to new and useful improvements in hair clippers and the like, and the primary object thereof is to provide means whereby the surface of the lower cutter plate carrying the guide studs is maintained true and unaffected by any adjustment of the studs as may be necessary to aline same with the top cutter plate.

In finishing the surface of cutters of the two plate type, such as in hair clippers, by polishing or buffing same, it is necessary that the studs of the lower cutter be removed so that the surface to be buffed is free of obstructions. The surfaces must be maintained true so that the cutters contact as near perfect as possible. After buffing, the studs are positioned and must be turned to aline, same with the guide slots of the upper cutter. If now in turning the studs, the heads of the latter disfigure or cause irregularities in the surface of the lower plate or cutter, a true contact with the upper plate or cutter will not be had.

This invention, briefly proposes an isolated contact area for engagement with the stud whereby regardless of the extent of adjustment of the latter, the contact surface of the plate will be unaffected and its trueness preserved.

30 In the drawings:—

Fig. 1 is a fragmentary plan view of the invention applied to hair clippers;

Fig. 2 is a section on line 2—2 of Fig. 1;

Fig. 3 is a top plan view of the lower cutter plate with the stud thereon; and

Fig. 4 is a view similar to Fig. 3, but with the stud removed.

In accordance with the art, illustrated in connection with hair clippers, 1 designates the bottom cutter plate, 2 the top cutter plate, the latter provided with slots 3 for receiving the usual guide studs 4.

The guide studs 4 are threaded into engagement with the bottom or lower cutter plate so that same are removable to enable buffing or polishing of the contact or upper face of the bottom plate. The above mentioned parts are of common construction, well known in the art.

50 The present invention resides in the formation of an annular groove 5 in spaced relation to the threaded hole 6 for reception of the threaded end of the guide stud 4 so as to provide a circular seat 7 isolated

from the remainder of the contact surface 55 of the bottom plate.

The groove 5 is of a width so as to enable the base of the head of the stud to overhang the groove and thus be prevented from engaging the contact surface of the 60 plate.

From the foregoing it will be seen that the invention provides an isolated area, remote from the contact surface of the plate, and within which area the base of the stud 65 head is confined, so that regardless of the degree or extent to which the stud is forcibly turned against the plate, the contact surface of the latter will not be affected. If the seat 7 is mashed or compressed by 70 turning of the stud the metal will flow laterally into the groove. The part of the plate surrounding the hole 6 is also slightly cut away at 9 so as to provide for any lateral flow of the metal of seat 7. 75

While the invention is disclosed in connection with hair clippers, still it is to be expressly understood that the same is equally applicable to other instances, where similar conditions exist. Consequently the present disclosure merely instances one example, or use of the invention.

Having thus described my invention what I claim as new and desire to secure by Letters Patent is:—

1. A member having a finished surface and a threaded aperture with a guide stud adjustable in said aperture and a seat compressible for the head of said stud isolated from the finished surface of the member so as to prevent contact of the stud head with such surface.

2. A member having a finished surface and an adjustable element provided with a contact face thereon and a compressible seat for said face of the element isolated from the finished surface of the member to prevent engagement of the contact face with the finished surface.

3. A member having a finished surface and a threaded aperture with a guide stud adjustable therein said member having a circular groove spaced from and surrounding the aperture to form a compressible seat for the head of the stud isolated from said finished surface so as to prevent contact of the stud head with such surface. 100

4. A member having a finished surface

- and a threaded aperture with a guide stud adjustable therein, said member having a circular groove spaced from and surrounding the aperture to form a seat for the head of the stud isolated from said finished surface so as to prevent contact of the stud head with such surface, the member being further formed with a circular groove extending into said aperture.
10. 5. A member having a finished surface and a threaded aperture with a guide stud adjustable in said aperture and having a pair of spaced circular grooves forming a circular seat for the head of the stud which grooves surround the aperture and isolate 15 the seat from the finished surface so as to prevent contact of the stud head with such surface.
6. A member having a finished surface and an aperture adapted to receive a stud provided with a squared head, and a compressible seat for said head on said member isolated from the finished surface thereof to prevent engagement of the head with the finished surface.

In testimony whereof I have signed my name to this specification.

GEORGE E. BUTLER.
